UNITED STATES PATENT OFFICE.

ERNEST B. COBB, OF JERSEY CITY, NEW JERSEY, ASSIGNOR TO STANDARD OIL COMPANY, OF BAYONNE, NEW JERSEY, A CORPORATION OF NEW JERSEY.

MANUFACTURE OF VISCOS WATER-WHITE OILS AND OTHER DECOLORIZED PRODUCTS OF PETROLEUM.

1,388,517.

Specification of Letters Patent.

Patented Aug. 23, 1921.

No Drawing.

Application filed July 23, 1914. Serial No. 852,671.

To all whom it may concern:

Be it known that I, ERNEST B. COBB, a citizen of the United States, residing at Jersey City, in the county of Hudson and State of New Jersey, have invented certain new and useful Improvements in the Manufacture of Viscous Water-White Oils and other Decolorized Products of Petroleum, of which the following is a specification.

10 This invention relates primarily to the manufacture from distillate from petroleum of the Pennsylvania type (or of a type similar thereto in the particulars hereinafter set forth) of oils, commercially known as white oils and so referred to hereinafter, whose color or colorlessness at least approximates that of burning oil (kerosene) of the commercial grade of water white and whose component hydrocarbons (for the most part at least) are higher in viscosity (as well as in boiling point) than the highest boiling of those normal to burning oil (kerosene); but, as will hereinafter more fully appear, the invention is not wholly limited to such manufacture. The highest boiling hydrocarbons normal to burning oil (kerosene) are considered to distil over from a laboratory flask at about 572° F. (vapor temperature) and the most viscous hydrocarbons normal thereto are considered to have viscosities of about forty seconds at 100° F. by a Saybolt's Universal viscosimeter. An equal volume of water will pass through such viscosimeter in thirty one seconds at 60° F. All the viscosities stated herein are to be determined by the same viscosimeter. The slightly colored liquid which results from first dissolving one - tenth gram of potassium chromate (K_2CrO_4) in one liter of distilled water and then diluting say five cubic centimeters of this solution to one hundred cubic centimeters with distilled water is considered to have about the maximum of color permissible in burning oil (kerosene) of the commercial grade of water white.

White oils have been used medicinally (in one mode at least by being taken into the stomach through the mouth) and also industrially (in one mode at least by being mixed with vegetable oil in the manufacture of soap). They have chiefly, it is believed, been products of Russian petroleum. Viscous Russian distillate is more easily decolor-

ized than Pennsylvania distillate of the same viscosity.

In accordance with the present invention (portions of which can be used separately) a suitable white oil stock is subjected to the action of sulfuric acid so as to form an acid sludge which is removed; the acid treated oil is distilled with use of special agency, such as injection of dry steam into the oil in distillation, to prevent (or restrict) the decomposition (cracking) of component hydrocarbons; the so obtained distillate is subjected to the action of sulfuric acid so as to form an acid sludge which is removed; and the oil, which has thus been twice subjected to the action of sulfuric acid and to a special intervening distillation, is filtered through solid decolorizing material, such as Florida clay, a material well known in petroleum refineries.

In this process part of the coloring matter of the stock is removed directly (that is to say, in the form of sludge) by the first acid treatment, and another part is so altered thereby as to become decomposable in the subsequent distillation of the acid treated oil, notwithstanding the employment of special agency (as aforesaid) to prevent (or restrict) decomposition (cracking) in said distillation; while the second treatment with sulfuric acid removes colored substances, some of which are no doubt formed in said distillation, but some of which may be unaltered constituents of the original stock; and the thus twice treated interveningly distilled oil is then further decolorized by the filtration. The sulfuric acid in each of the treatments therewith, moreover, it is believed, so alters some of the coloring matter as to make it more susceptible to removal by subsequent filtration of the oil than it otherwise would be; and said filtration may remove some unaltered coloring matter of the original stock, as well as colored substances produced by the action of one or more of the preceding operations on original (colored or uncolored) constituents of the stock.

In carrying out the process the following special features may well be employed.

First. The stock operated upon may well be obtained as distillate in a distillation in which special agency is employed to pre-

vent decomposition of component hydrocarbons.

Second. The stock operated upon may well be composed of hydrocarbons within a 5 comparatively narrow range of gravities; such stock, for example, as would be collectible as distillate in an appropriate distillation during the interval between the time at which the stream at the condenser 10 outlet attains a predetermined gravity (whatever the operator may prefer) and the time at which said stream becomes say not more than about ten degrees B. heavier.

Third. The stock operated upon may well 15 consist (even when composed, as just mentioned, of hydrocarbons within a comparatively narrow range of gravity) of a certain percentage which (consistently with the obtaining of the desired white oil) can be 20 rejected after the earlier of the treatments with sulfuric acid at the beginning of the succeeding special distillation.

Fourth. The stock may well have about 25 the viscosity desired in the finished oil, neither largely (if at all) more viscous nor largely (if at all) less viscous than the finished oil to be obtained therefrom.

Fifth. The stock may well contain only 30 a small percentage (if any) of hydrocarbons too viscous to be desirable ingredients in the finished oil to be obtained from said stock.

Sixth. Stronger acid than commercial acid of 1.835 specific gravity (which ordinarily contains and which is regarded herein as containing about 92.5% to 93% by weight of sulfuric monohydrate H_2SO_4 , and about 7% to 7.5% of water) may well be employed in each of the treatments with sulfuric acid. Sulfuric anhydrid SO_3 is regarded herein as one form of such stronger acid, as well as fuming sulfuric acid of all strengths and non-fuming acid which contains in excess of 93% sulfuric monohydrate. Good results have been obtained 45 with fuming sulfuric acid containing twenty parts by weight of sulfuric anhydrid and eighty parts by weight of sulfuric monohydrate, the same being a commercial article and being referred to hereinafter as 20% 50 fuming sulfuric acid.

Seventh. The initial temperature for each of the treatments with sulfuric acid may well be not higher than about 70° F., say between about 70° F. and about 20° F., 55 and even lower, if desired; and it is believed that improvement would result from each lowering of said initial temperature from 70° F. downward to at least as low as 20° F. The chemical reactions tend to raise the 60 temperature. Special cooling to restrict such rise is considered unnecessary; but the use of the same is not necessarily excluded.

Eighth. The earlier of the treatments with sulfuric acid may well be more energetic than the later of them (as by using

a larger proportion of sulfuric acid of given strength, or the same proportion of a stronger acid, or both a larger proportion and a greater strength of acid in the earlier than in the later treatment).

Ninth. The acidity of the oil after the earlier of the treatments with sulfuric acid may well be neutralized with alkaline material (as caustic soda lye) prior to distillation. The spent lye is removed by settling.

Tenth. Acid treated stock which contains only a small percentage (if any) of hydrocarbons too viscous to be desirable ingredients in the finished oil to be obtained from 80 said stock may well be distilled approximately at least to dryness; and, inasmuch as in distilling with injection of dry steam (or of any aeriform fluid) into the oil in distillation there must always be enough 85 material in the still to cover the injecting pipes, resort may well be had to the hereinafter described mode of distilling with injection of aeriform fluid in order to distil the said acid treated stock to dryness or approximately so.

Eleventh. The stock which has been twice subjected to treatment with sulfuric acid and to the intervening distillation may well be filtered in an acid condition.

Twelfth. The so treated and interveningly distilled stock may well be filtered through solid decolorizing material which is partially exhausted and afterward through that which is exhausted in less degree (if at all), the 100 said material, after losing some of its original decolorizing power, being used in an earlier stage of the filtration.

Thirteenth. The filtrate (filtered oil) may well be subjected to free steam under such 105 conditions of temperature and pressure that the steam in part condenses and in part passes off in aeriform condition, thus washing out those impurities which may be soluble in the hot water of condensation and 110 carrying those away in aeriform condition which will volatilize.

Fourteenth. The amount of solid decolorizing material necessary to a given decolorizing effect, by the combined operation of the 115 two treatments with sulfuric acid, the intervening special distillation and the subsequent filtration through said solid decolorizing material, would in general be less the more energetic the treatments with sulfuric acid; 120 and conversely; but the changes are not in constant ratio; and it is estimated that in making a water white oil of about eighty seconds viscosity at 100° F. it would under existing conditions be financially unprofitable to use on the one hand as much as the equivalent (in content of sulfur trioxid in the form of sulfuric anhydrid or monohydrate, or both) of twenty gallons of 20% 125 fuming sulfuric acid to the barrel of stock 130

subjected thereto, or, on the other hand, sulfuric acid treatments so little energetic that the equivalent (in decolorizing power) of more than three hundred pounds of freshly calcined Florida clay to the barrel of oil subjected to the filtering operation would be needed (after the two treatments with sulfuric acid and the intervening special distillation) in order to render the so filtered and subsequently steamed oil water white; and the amount of sulfuric acid (of appropriate strength) employed may well be kept within these limits in obtaining a decolorized oil up to about eighty seconds viscosity at 100° F., whatever type of petroleum may be operated upon, with permissible increases in the amounts mentioned of solid decolorizing material and of sulfuric acid respectively for decolorizing oil of higher viscosity.

While, however, these special features, all and singular, may well be used, at least in some cases, in performing the general process aforesaid, if it should be preferred in any case to omit any one or more, or even all, of said features, such omission can be made within the limits of the invention. Thus the stock operated upon may be obtained otherwise than as distillate in a distillation in which special agency is employed to prevent decomposition of component hydrocarbons; its hydrocarbons may have a wider range of gravities than ten degrees B.; it may be practically free from hydrocarbons to be rejected at the beginning of the intervening special distillation; its viscosity need not be about the same as that desired in the finished oil; it may contain more than a small percentage (as mentioned) of hydrocarbons too viscous to be desirable ingredients in the finished oil.

The use of sulfuric acid of 1.835 specific gravity (even acid of less strength) instead of or in addition to stronger acid is not necessarily excluded in either or in each of the treatments; nor is the use of temperatures above 70° F. initial; and the later of the two treatments with sulfuric acid may be as energetic as or more energetic than the earlier of them. The acidity of the oil is not necessarily neutralized before the special distillation thereof. Where stock is used which contains considerable hydrocarbons which would be undesirable ingredients in the finished oil and are of sufficiently high boiling point to remain in the still to the close of the distillation, an appropriate undistilled residue may well be left in the still, instead of distilling the stock to dryness or approximately so in said special distillation. The stock need not be filtered in acid condition. Neutralization of acidity after the later treatment with sulfuric acid and prior to the filtration is not necessarily excluded. Filtration may be performed otherwise than in the special manner mentioned. Washing of the filtrate (filtered oil) with hot water and evaporation of vola-

tile impurities (one or other or both) can be performed otherwise than by injection thereto of free steam under conditions of temperature and pressure at which partial condensation takes place of the injected steam; and the finishing of the oil in modes which do not involve such washing and evaporation (or either of them) is not necessarily excluded. In fact, if the filtered oil should be satisfactory, it need not be further operated upon. The proportion of sulfuric acid and the proportion of solid decolorizing material are not necessarily either of them within the limits mentioned herein above.

Part of the special features mentioned can be used (within the scope of the invention) otherwise than in performing the process mentioned.

An oil of about eighty seconds viscosity at 100° F. and having appreciably less color than the maximum permissible in burning oil of the commercial grade of water white has been obtained by using about six gallons (combined amount in the two treatments) of 20% fuming sulfuric acid per barrel (40 gallons) of stock and about fifty five pounds of Florida clay to the barrel (40 gallons) of oil subjected to the filtering operation; but it is anticipated that in large scale commercial working a similar oil can be obtained with smaller amounts of the two decolorizing agents (acid and clay).

The following is a detailed description of making a white oil of about eighty seconds viscosity at 100° F. from distillate from petroleum of the Pennsylvania type obtained from wells in West Virginia and having in its crude state a gravity of about 43° B., the crude oil being distilled with reference to cylinder stock (to be obtained as an undistilled residue) and other products (to be made from distillate) and the white oil stock being derived from a part of the distillate. This description is by way of example and illustration and is not intended to confine the invention thereto. Modifications within the scope of the invention can in fact be made indefinitely by addition, subtraction, substitution or otherwise so long as the substance is taken of any one or more of the claims at the close of this specification.

The crude petroleum is distilled in an externally heated still with injection of dry steam into the oil in distillation, as customary in lubricating works; and a cut is made which will contain hydrocarbons of the viscosities desired in the white oil and which may well also be such as it would be desirable to make apart from the manufacture of white oil therefrom, say a cut between 39° B. and 34.5° B. (gravity of stream at the condenser outlet at beginning and end respectively of the cut). This particular cut would be reduced (with or without prior chilling and pressing for paraffin wax, as

may be preferred) until the residual oil should have about the viscosity desired in the white oil to be made (last runnings say about 37° B. in gravity), dry steam being injected into the oil under reduction to prevent decomposition. The residue would form the white oil stock and may have a gravity of about 34° B. It is more homogeneous than a distillate collected in the crude oil run would be; although a cut of distillate from the crude oil run can be used. Additional distillations can, on the other hand, be made, if desired. The stock is cooled to a temperature of about 20° F. (or as much below 70° F. as may be preferred) and is introduced into an agitator of the customary funnel bottomed upright cylindrical form until the desired charge has been received. The herein above mentioned 20% fuming sulfuric acid, also cooled to about 20° F. or as much below 70° F. as may be preferred, is then supplied to the agitator in the proportion say of thirteen volumes of said acid to one hundred volumes of white oil stock. The oil and acid are agitated say with injected air (as customary in treating petroleum distillates with commercial sulfuric acid of 1.835 specific gravity) until the effect of the sulfuric acid is exhausted. The sludge is allowed to settle and is drawn off. The acid treated oil is transferred to a clean agitator; and its acidity is neutralized by agitation with any appropriate alkaline material, say caustic soda lye, of 1.080 specific gravity. The spent alkali is allowed to settle and is drawn off. The neutralized unwashed oil is transferred to a still and is distilled by externally applied heat aided by injection of dry steam into the oil in distillation until the residue in the still represents say ten per cent. by volume of the still charge. This residue is suitably cooled; and enough neutralized oil to complete a new charge is run in. This new charge is distilled down to a 10% residue, as before. Other charges are similarly formed until a charge is obtained which can be distilled to dryness, or nearly so, and yet leave sufficient residue to cover the steam injecting pipes. This residue (amounting to about one or two per cent. by volume of the aggregated still charges) is removed to be disposed of as may be preferred; and the still is further cleaned, if necessary, for the next run. Residues can be accumulated in other ways for distillation later to dryness, or nearly so. Neutralized unwashed oil can be run into the still during the distillation; although it is considered better to introduce it as a distinct operation after a preceding charge has been distilled off to the temporarily desired extent. The residue left by each of a number of runs could be withdrawn and stored until enough should accumulate to make a still charge; whereupon

the accumulated residues could be charged into a still and distilled down to dryness, or nearly so. Yet other modes could be employed.

In distilling the acid treated oil (suitably neutralized) the distillate is collected separately so long as the component hydrocarbons are of an undesirably low viscosity. In the present example this undesirable distillate may amount to about fourteen per cent. by volume of the oil subjected to the distillation; and all the rest of the distillate is utilized.

By excluding a certain portion of the distillate, the advantage is gained of making the utilized distillate more homogeneous without any extra distillation for the purpose, a double function being thus performed by the one distillation. On the other hand, by minimizing the exclusions sulfuric acid is economized in the first treatment therewith.

The desirable distillate, amounting to about eighty six per cent. of the total obtained in this example, is agitated with say three per cent. by volume of the aforesaid 20% fuming sulfuric acid, and separated from the sludge by settling and drawing off the latter. This three per cent. would be about two per cent. of the white oil stock (or eight-tenths of a gallon of the sulfuric acid per barrel of said stock); since the desirable distillate in the example would be about sixty eight per cent. of said stock.

The acid treated oil is filtered through Florida clay without prior neutralization or washing. It could, however, be neutralized, if preferred; but the acidity of the oil is found to assist the filtering operation. Florida clay which has been freshly calcined would best be used.

The filtrate is steamed until it is considered by the operator to be odorless and tasteless, or as nearly so as may be desired. It is freed from moisture and then constitutes finished white oil of about eighty seconds, more or less, viscosity at 100° F., the yield being about sixty two per cent of the white oil stock. Its gravity should be appreciably less than that of said stock, say about 36.3° B. as against 34° B.

The Florida clay may well be in pieces small enough to pass through a sieve of thirty meshes to the linear inch and large enough to be caught by one with sixty meshes. It may be placed in one or more filtering vessels on cloth over perforated bottoms and can be used until the filtrate goes off in color (no longer yielding an oil which is of the desired colorlessness after steaming). It is thereupon renewed in whole or in part. It is advantageous to add fresh clay at the outlet end of the filtering material; so that the oil passes through successive bodies of clay in decreasing extent of use; since in this way a substantial saving

in the mount of clay per barrel of oil can be made without loss in decolorizing effect. In other words, it has been discovered that the power of clay to remove one part of 5 the coloring matter of viscous petroleum is retained and can be utilized after its power to attract another part thereof to itself has become exhausted, or practically so. While other modes are not excluded for carrying 10 out this special improvement, what is considered best is to use say four filtering vessels, each five feet in diameter and fourteen feet high, filled twelve feet deep with the clay, and to arrange for passing the oil 15 through said vessels in series in such manner that the series can begin with any vessel and that any vessel can be cut out when desired. Useful arrangements for the purpose are known in other connections. Starting 20 say with three vessels in series and the fourth cut out and filled with fresh clay, when the filtrate tends to go off in color said fourth vessel is included as the last in the series; and the first vessel of the series is cut out. 25 This last mentioned vessel is then emptied and refilled. When the filtrate again tends to go off in color, the vessel is again included in the series, but this time at the tail end thereof. What was originally the second vessel of the series is cut out at the same 30 time or when desired. And so filtration proceeds practically without interruption first through partially exhausted clay and then through that which is less and less exhausted (if exhausted at all). Under the 35 conditions mentioned about fifty five pounds of fresh clay per barrel (40 gallons) of filtered oil have been found to give a water white oil appreciably less colored than the 40 dilute solution herein above mentioned of potassium chromate.

The steaming may well be performed under atmospheric pressure at a temperature of about 212° F. The hot water of condensation washes out some impurities; and others 45 (such as a little sulfur dioxide and some cracked hydrocarbons, amounting to perhaps about one-half per cent. of the steamed oil) pass off in the current of uncondensed steam. 50 In obtaining products from petroleum instead of reducing (partially distilling) the crude petroleum for cylinder lubricating stock and distillate as aforesaid, it is more common to distill the crude petroleum completely 55 for distillate, only dry coke remaining as residue. Such complete distillation is usually performed without injection of aeriform fluid into the oil in distillation, and is, therefore, accompanied with more 60 composition (cracking) of component hydrocarbons than occurs in said reduction for cylinder stock; so that distillate from said 65 complete distillation is less suitable for white oil stock than distillate of the same viscosity from said reduction. If necessary or expe-

dient to utilize such inferior stock, however, it would be best to use distillate obtained in reducing the pressed paraffin distillate in the customary manner for obtaining therefrom heavy lubricant stock (as residue) and 70 other products (as distillate), such reduction being performed with injection of dry steam into the oil. A cut of distillate may well be taken which would contain hydrocarbons of the viscosities desired in the oil 75 to be made; and further reduction or other distillation of said cut can be performed if necessary or expedient in order to secure stock of the desired viscosity.

The manner of operating upon such stock 80 would not be so different from what has been already described as to require further description.

Herein above injection of dry steam has been described as the best mode of avoiding decomposition in distillation; other modes are not necessarily excluded. Injection of other inert aeriform fluid also tends to do so. Distillation under subatmospheric pressure, for example, might serve, 85 especially if what would be considered in the art as a high vacuum should be employed. A partial vacuum could be used with or without injection of dry steam or of other inert aeriform fluid. 90

While the invention relates primarily to making white oils from distillate from petroleum of the Pennsylvania or similar type, it is not necessarily limited exclusively thereto. It is believed that it can usefully 100 be applied to the manufacture of white oils from distillate from petroleum of any other type. Less sulfuric acid and clay, it is believed, would be required for the manufacture of a white oil of given viscosity 105 from Russian than from Pennsylvania distillate. 95

Crude petroleum of the Pennsylvania type has a gravity which ranges between about 40° B. and about 45° B.; it has an 110 amber color; it is suitable for the manufacture of cylinder lubricating stock by reduction with injection of dry steam; it contains paraffin wax in workable proportion; and it is comparatively free from hydrocarbons of the aromatic (closed chain) series. Its component hydrocarbons of boiling points normal to burning oil (kerosene) (302° F. to 572° F.) are lighter in gravity than the hydrocarbons of the same boiling points in Russian petroleum. Any petroleum is considered to be of a type similar to the Pennsylvania type in the particulars herein set forth when it possesses sufficient of the properties mentioned to ally it to 115 Pennsylvania rather than to Russian petroleum. 120

While the invention relates primarily to white oils, that is to say, to viscous oils which are water white at least approxi- 130

mately in color; it is evident that viscous oils not water white in color even approximately could be made from viscous distillate by the described procedure using suitably smaller amounts of one or other or of each of the decolorizing agents per barrel of oil subjected to them respectively; and such manufacture may well involve advantages over the prior state of the art, at least for some purposes. It is also believed that oils of non-petroleum origin, but analogous thereto, such as shale oils, for example, can be decolorized in accordance with the invention to a useful extent; and the decolorizing of hydrocarbon products not liquid at 60° F. under atmospheric pressure is not necessarily excluded from the scope of the invention. The "hydrocarbon oil" of the present specification is, therefore, primarily, but not exclusively, a product of Pennsylvania or similar petroleum; it may be a product of petroleum of any other type; or it may be obtained from a material (such as shale oil) suitably analogous to petroleum, but not in all respects similar thereto. It is to be regarded herein as "decolorized" primarily, but not exclusively, when it is so far freed from coloring matter as to be at least approximately water white after it shall have been steamed as herein above mentioned; it is intended to be so designated also whenever it has been rendered notably lighter in color than the stock whence derived; although it may not be approximately water white. Such "decolorized hydrocarbon oil" to be "of viscous character" must have a viscosity above forty seconds at 100° F.

The "solid decolorizing material" of the present specification is primarily, but not exclusively, clay; it is also intended by said expression to cover other solid decolorizing material through which oil can be filtered.

I claim as my invention or discovery:

1. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, substantially as described.

2. The process of making a decolorized hydrocarbon oil of viscous character, consisting in (1) subjecting stock which has

a viscosity above forty seconds at 100° F. and which has been obtained as distillate in a distillation with use of special agency to prevent decomposition of component hydrocarbons to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, substantially as described.

3. The process of making a decolorized hydrocarbon oil of viscous character, consisting in (1) subjecting stock which has a viscosity above forty seconds at 100° F. and which would be collectible as distillate within a range of not more than about ten degrees B. at the condenser outlet to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, substantially as described.

4. The process of making a decolorized hydrocarbon oil of viscous character, consisting in (1) subjecting stock which has a viscosity above forty seconds at 100° F. and which would be collectible as distillate within a range of not more than about ten degrees B. at the condenser outlet to the action of sulfuric acid so as to form an acid sludge which is removed, (2) distilling the acid treated oil with use of special agency to prevent the decomposition of component hydrocarbons and with collection of the major part but not of all the obtainable distillate and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, substantially as described.

5. The process of making a decolorized hydrocarbon oil of viscous character, consisting in (1) subjecting stock which has a viscosity above forty seconds at 100° F. and not more than a few seconds different from

that to be obtained in the decolorized oil to the action of sulfuric acid so as to form an acid sludge which is removed, (2) distilling the acid treated oil with use of special agency to prevent the decomposition of component hydrocarbons and so obtaining distillate which has a viscosity not more than a few seconds different from that of said stock, (3) subjecting said distillate to the action of sulfuric acid so as to form an acid sludge which is removed, and (4) filtering the oil which has thus been twice subjected to sulfuric acid and to an intervening distillation through solid decolorizing material, substantially as described.

6. The process of making a decolorized hydrocarbon oil of viscous character, consisting in (1) subjecting stock which has a viscosity above forty seconds at 100° F. and whose most viscous hydrocarbons would be desirable in the decolorized oil to the action of sulfuric acid so as to form an acid sludge which is removed, (2) distilling the acid treated oil to at least approximate dryness with use of special agency to prevent the decomposition of component hydrocarbons and so obtaining distillate which has a viscosity above forty seconds at 100° F. and which contains the last runnings of said distillation, (3) subjecting said distillate to the action of sulfuric acid so as to form an acid sludge which is removed, and (4) filtering the oil which has thus been twice subjected to sulfuric acid and to an intervening distillation through solid decolorizing material, substantially as described.

7. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, sulfuric acid stronger than commercial acid of 1.835 specific gravity being employed in one at least of the treatments mentioned, substantially as described.

8. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special

agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, the initial temperature for one at least of said treatments with sulfuric acid being between 70° and 20° F. and lower if desired, substantially as described.

9. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, the treatment with sulfuric acid which precedes said intervening distillation being more energetic than that which follows the same, substantially as described.

10. The improvement in distilling hydrocarbon oil of viscous character with injection of aeriform fluid thereinto, consisting in making a number of runs which are performed with injection of aeriform fluid into the oil in distillation and are carried to such extent only that a considerable percentage of each charge remains undistilled, accumulating this residual oil from an appropriate number of such runs, and completing the distillation of the so accumulated oil with injection of aeriform fluid thereinto until a condition of at least approximate dryness is attained, substantially as described.

11. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an

intervening distillation in acid condition, through solid decolorizing material, substantially as described.

12. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillates which has a viscosity above forty seconds at 100° F., (3) subjecting said distillate to the action of sulfuric acid so as to form an acid sludge which is removed, (4) filtering the oil which has thus been twice subjected to sulfuric acid and to an intervening distillation through solid decolorizing material, and (5) washing the filtrate oil with hot water, substantially as described.

13. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, (4) filtering the oil which has thus been twice subjected to sulfuric acid and to an intervening distillation through solid decolorizing material, and (5) partially distilling the filtrate oil with injection of aeriform fluid into the same, substantially as described.

14. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, (4) filtering the oil which has thus been twice subjected to sulfuric acid and to an intervening distillation through solid decolorizing material, and (5) then injecting steam into the filtrate oil under such conditions of temperature and pressure that the steam will in part condense in the oil and in part pass off in aeriform state, substantially as described.

15. The process of making a decolorized hydrocarbon oil of viscous character, consisting in (1) subjecting stock which has a

viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, sufficiently energetic treatments with sulfuric acid being employed for the decolorized oil to be obtained with a proportion of solid decolorizing material equivalent in decolorizing power to not more than about three hundred pounds of fresh Florida clay per barrel of oil subjected to the filtering operation in the case of an oil of about eighty seconds viscosity at 100° F. and with corresponding increase in the proportion of solid decolorizing material for more viscous oil, substantially as described.

16. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid decolorizing material, the total sulfuric acid being equivalent in content of sulfur trioxid to not more than about twenty gallons of 20% fuming sulfuric acid per barrel of stock in the case of an oil of about eighty seconds viscosity at 100° F. and with corresponding increase in the proportion of sulfuric acid for more viscous oil, substantially as described.

17. The process of making a decolorized hydrocarbon oil of viscous character, consisting in (1) subjecting stock which has a viscosity above forty seconds at 100° F. to the action of sulfuric acid so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation through solid de-

colorizing material, sufficiently energetic treatments with sulfuric acid being employed for the decolorized oil to be obtained with a proportion of solid decolorizing material equivalent in decolorizing power to not more than about three hundred pounds of fresh Florida clay per barrel of oil subjected to the filtering operation and the total sulfuric acid being equivalent in content of 5 sulfur trioxid to not more than about twenty gallons of 20% fuming sulfuric acid per barrel of stock in the case of an oil of about eighty seconds viscosity at 100° F. and with corresponding increase of the solid 10 decolorizing material and the sulfuric acid 15 respectively in the case of more viscous oil, substantially as described.

18. The process of making a decolorized hydrocarbon oil of viscous character, consisting in (1) subjecting stock which has a viscosity above forty seconds at 100° F. to the action of sulfuric acid which consists at least in part of sulfuric anhydrid, so as to form an acid sludge which is removed, (2) distilling the acid treated oil with use of special agency to prevent the decomposition of component hydrocarbons and so obtaining distillate which has a viscosity above forty seconds at 100° F., (3) subjecting said distillate to the action of sulfuric acid so as to form an acid sludge which is removed, and (4) filtering the oil which has thus been twice subjected to sulfuric acid and to an intervening distillation 25 through solid decolorizing material, substantially as described.

19. The process of making a decolorized hydrocarbon oil of viscous character, consisting in (1) subjecting stock which has a 30 viscosity above forty seconds at 100° F., to the action of sulfuric acid which consists at

least in part of sulfuric anhydrid, so as to form an acid sludge which is removed, (2) distilling the acid treated oil with use of special agency to prevent the decomposition 45 of component hydrocarbons and so obtaining distillate which has a viscosity above forty seconds at 100° F., (3) subjecting said distillate to the action of sulfuric acid which consists at least in part of sulfuric anhydrid, so as to form an acid sludge which is removed, and (4) filtering the oil which has thus been twice subjected to sulfuric acid and to an intervening distillation through solid decolorizing material, substantially as 50 described.

20. The process of making a decolorized hydrocarbon oil of viscous character, consisting in (1) subjecting stock which has a viscosity above forty seconds at 100° F. to 55 the action of sulfuric acid stronger than commercial acid of 1.835 specific gravity so as to form an acid sludge which is removed, (2) subjecting the acid treated oil after neutralization with alkaline material to distillation with use of special agency to prevent the decomposition of component hydrocarbons and so obtaining distillate which has a viscosity above forty seconds at 100° F., (3) subjecting said distillate to the action of 60 sulfuric acid so as to form an acid sludge which is removed, and (4) filtering the oil which has thus been twice subjected to sulfuric acid and to an intervening distillation 65 through solid decolorizing material, substantially as described.

In testimony whereof I affix my signature in presence of two witnesses.

ERNEST B. COBB.
